UNITED STATES PATENT OFFICE.

JAMES E. LAPPEN, OF LE ROY, MINNESOTA, ASSIGNOR TO LE ROY FIBRE COMPANY,
OF ST. PAUL, MINNESOTA, A CORPORATION OF MINNESOTA.

FLAX-FELT MACHINE.

1,023,473.

Specification of Letters Patent. Patented Apr. 16, 1912.

Application filed February 17, 1908. Serial No. 416,165.

To all whom it may concern:

Be it known that I, JAMES E. LAPPEN, a citizen of the United States, residing at Le Roy, in the county of Mower and State of Minnesota, have invented certain new and useful Improvements in Flax-Felt Machines; and I do hereby declare the following to be a full, clear, and exact description of the invention, such as will enable others skilled in the art to which it appertains to make and use the same.

My invention has for its object to provide an improved fiber board machine, and to this end it consists of the novel devices and combinations of devices hereinafter described and defined in the claims.

The improved machine illustrated in the drawings was especially designed for carrying out the process disclosed and claimed in my co-pending application S. N. 330,274, filed August 12, 1906, entitled "Process of producing flax felt," and in making the so-called flax felt or flexible fiber board disclosed and claimed in my Patent, 908,681, of January 5th, 1909, entitled "Flax felt."

The improved machine is illustrated in the accompanying drawings, wherein like characters indicate like parts throughout the several views.

Referring to the drawings, Figures 1 and 1^a are supplemental views in vertical section, taken longitudinally and centrally through the improved machine, said Fig. 1 showing the right hand portion, and said Fig. 1^a showing the left hand portion of said machine, directions being taken with respect to a person viewing said figures. Fig. 2 is a fragmentary view in plan illustrating the construction of the main endless apron of the machine. Fig. 3 is a fragmentary view in plan, showing a portion of one of the so-called secondary pressure rollers. Fig. 4 is a plan view of the right hand or receiving portion of the machine, some parts being removed and some parts being broken away. Fig. 5 is a transverse vertical section taken approximately on the line x⁵ x⁵ of Fig. 1. Fig. 6 is a detail in horizontal section, taken on the line x⁶ x⁶ of Fig. 5, some parts being broken away. Fig. 7 is a view in side elevation, showing the left hand or delivery end portion of the machine, some parts being indicated partly by dotted lines; and Fig. 8 is a plan view of the parts shown in Fig. 7.

In the description of this improved machine, the fiber treated will be assumed to be flax, and the liquid in which it is submerged for treatment will be assumed to be water. The vessel in which the water is contained is in the form of a long trough 1 which, as shown, is supported by suitable legs 2. The flax fiber is indicated by the character y, and the level of the water contained in the trough 1 is indicated by the character z. The fiber y, as shown, is delivered into the right hand or receiving end of the trough 1 by an inclined spout 3. Rigidly secured in the receiving end of the trough 1, below the level of the water z, is a toothed concave 4 with which co-operates a toothed cylinder 5, the shaft 5^a of which is mounted in suitable bearings 6 on the sides of the trough 1, and, as shown, is provided at one end with a pulley 7, and at its other end with a sprocket 8. A power driven belt 9 runs over the pulley 7 to impart rotary motion to the cylinder 5 in the direction of the arrows marked thereon in Fig. 1.

Suitably secured within the trough 1, just in front of the concave 4, is a perforate or reticulate deck 10 that is submerged in the water z. Working immediately above this perforate deck 10 are several so-called agitators made up, as shown, of shafts 11 having spirally arranged teeth 12. The shafts 11 are mounted in suitable bearings 13 on the sides of the trough 1, and the teeth 12 are arranged to work in the water z close to the upper surface of the deck 10. The intermediate shaft 11 is provided at one end with a sprocket 14 over which and the sprocket 8 of the cylinder shaft 5^a a sprocket chain 15 runs. At its other end, said intermediate shaft 11 is provided with two sprockets 16 and 17. A sprocket chain 18 runs over the sprocket 17 and over a sprocket 19 on the right hand shaft 11, while a sprocket chain 20 runs over the sprocket 16 and over a sprocket 21 on the left hand shaft 11. Thus the three agitators are driven from the cylinder shaft 5^a. As shown, a hood 22 covers the cylinder and the three agitators.

A long endless traveling apron or carrier belt 23 receives the fiber from the perforate deck 10 at a point below the upper surface of the water z and carries the same gradually upward and toward the delivery or

left hand end of the machine. This apron 23, at its receiving portion, runs over an idle guide roller 24 that is submerged in the water z , mounted in suitable bearings on 5 the sides of the trough 1. The delivery portion of this apron 23 runs over a large roller 25 which, as shown, is suitably journaled in a heavy frame located beyond the delivery end of the trough 1 and made up of laterally spaced pedestal plates 26 and tie bars 27. At the delivery end of the trough 1, the belt 23 runs over idle guide rollers 28 and 29 mounted, respectively, on the adjacent end of the trough 1 and on a deck 15 frame 30, which latter, as shown, connects the delivery end of the trough 1 to the pedestal plates 26 and supports an imperforate deck section 31, over which the upper portion of said apron 23 runs. At the right of 20 the rollers 28 and 29, the upper portion of the apron 23 runs over an inclined open deck, made up, as shown, of longitudinally extended slats 32 and transverse tie slats 33.

In accordance with one feature of this invention, the endless apron or carrier belt 23 is made up of a reticulate cloth fabric 23^a and a woven wire fabric 23^b, as shown only in Fig. 2. The wire fabric 23^b has very 25 much coarser mesh than the cloth fabric 23^a and serves to give required strength to the said apron, while the cloth fabric 23^a, being of smaller mesh, permits the free escape of water therethrough, but holds the fiber and prevents the same from becoming entangled 30 with the wire fabric 23^b.

Overlying the large roller 25 is a similar roller 34 that co-operates therewith to make up what is herein designated as a pair of primary pressure rollers. The shaft of this 40 roller is mounted in bearings 35 which, in turn, are mounted for vertical adjustments in suitable seats formed in the pedestal plates 26. The bearings 35 are yieldingly pressed downward by coiled springs 36 45 which, in turn, are arranged to be adjusted by screws 37 that have threaded engagement, as shown, with top bars 26^a of said pedestal plates.

Located at the left of and horizontally 50 aligned with the so-called primary pressure rollers is a similar pair of so-called secondary pressure rollers 38 and 39. The shaft of the upper roller 39 is journaled in a bearing 40 which, in turn, is mounted for vertical movements in suitable seats formed in the pedestal plates 26. The bearings 40 are yieldingly pressed downward by coiled springs 41 that are subject to screws 42 which have threaded engagement with the 55 plate bars 26^a.

The shaft 25^a of the roller 25 is provided at one end with a large spur gear 43, and at its other end with a sprocket 44. A sprocket chain 45 runs over the sprocket 60 44 and over a sprocket 46 on the shaft 38^a

of the roller 38. A power driven pinion 47 meshes with a large gear 43. By the connections just described, the two lower rollers 25 and 38 are positively driven in the directions indicated by the arrows marked thereon in Fig. 1^a. Working between the rollers 25 and 38 is a short supporting belt 48 that runs over small rollers 49 and 50 mounted in suitable bearings in the pedestal plates 26. The shaft of the roller 49 is provided with a sprocket 51 with which the chain 45 also engages so that said belt 48 is driven in the same direction as the rollers 25 and 38. 70

The numeral 52 indicates a suitable carrier, shown as in the form of a slatted belt 80 arranged to run over a suitable roller 53 and a co-operating roller (not shown) for carrying the finished felt or board to a drier, or elsewhere.

The secondary pressure rollers are preferably faced or covered with woven wire fabric 54, as best shown in Fig. 3. 85

Overlying the apron 23 and extending transversely across the same, approximately at the point where the said apron leaves the upper surface of the water z , is a vibratory tapper, preferably in the form of an approximately flat tamping plate 55 having rounded edges. As shown, this tamping plate 55 is provided with transversely reduced vertically extended end portions 56 that work in vertical grooves 57 of guide pedestals 58 rigidly secured to the sides of the trough 1. Mounted in the upper portions of the guide pedestals 58 is a crank 90 shaft 59. This crank shaft is connected by a pair of links to the opposite end portions of the tamping plate 55. As shown, the said links are made up of body sections 60 and threaded rod sections 61, the latter of 95 which engage nuts 62 countersunk into the tamping plate 55. The body sections 60 have a slight pivotal movement on the rod sections 61, so as not to interfere with the true vertical movements of the tamping plate. On one end of the crank shaft 59 is a pulley 63 over which a power driven belt 64 runs to impart rotary motion to the said 100 crank shaft and, hence, a vertical vibratory movement to the tamping plate 55. 105

Secured to the sides of the trough 1, just in front of the tamping plate 55, is a pair of reversely set gathering boards 65 which are preferably made adjustable by means of slotted brackets 66 and set screws 67. Secured to the sides of the deck frame 30, just in front of the primary rollers 23-34 is another pair of gathering boards 68 which are preferably made adjustable by means of slotted brackets 69 and set screws 70. Secured to the pedestal plates 26, between the rollers 34 and 39, is still another pair of gathering boards 71. 110

The flax fiber y which is treated in this machine may be obtained either directly 115

from the flax straw as it comes from a threshing machine, or from so-called upholstering tow, which, as well known, is such flax straw after it has been subjected to the 5 action of a tow machine for knocking off therefrom more or less of the shive. For all the better grades of the fiber board, tow is used as the material from which to obtain the fiber. That tow is first cooked in an 10 alkaline or other equivalent chemical solution in a suitable digester for a suitable length of time in order to soften up the fibers and remove more or less of the gums from the bast. These gums must be removed 15 to a sufficient extent to prevent the fiber board from fermentation when put into service under the action of heat and moisture. The softening up of the fibers is also a matter of large importance in order to get the 20 material into the best condition for treatment by this machine, and whatever additional manipulation is necessary to get the fibers felted together into the fiber board. The cooking is especially necessary in order 25 to soften up the shive, as the shive in its raw state is very hard and very stubborn. After the tow has been cooked in an alkaline or equivalent chemical solution of the proper strength for the proper length of 30 time, however, this shive will be sufficiently softened up to enable the felting together of the shive and the bast while the disintegrated fibrous stock is held in suspension in the water of the felting vat. The bast is 35 naturally of such density that it will be held in suspension in the water and the shive is made of sufficient density for that purpose or result by the said cooking action. Moreover, most of the shive is adherent to 40 the bast and remains adherent to the bast after the cooking action, and even after the stock has been disintegrated by the devices of this machine. There will, however, be some of the bast in a free or loose condition 45 in respect to the shive, and some of the shive free or entirely detached from the bast. The bast is long and the shive is relatively short, but inasmuch as both the bast fiber and the shive will be held in suspension in the water 50 of the felting vat after the cooked stock has been torn apart and disintegrated by the devices of this machine, it follows that they can be intertwined and interlapped in such a way that they will thoroughly felt together. 55

The operation of the machine is substantially as follows: The flax fiber introduced into the delivery end of the trough 1 will be thoroughly disintegrated while submerged 60 in the water by action of the toothed cylinder 5 and toothed concave 4, and will be delivered above the perforate deck 10 where it becomes subject to the rotary agitators 11-12, and by the latter it will be further loosened up, spread out and commingled 65

with the water. The said agitators also serve to carry the loosened and thoroughly soaked fiber forward onto the delivery portion of the traveling apron 23. By this traveling apron the fiber is gradually raised 70 in the water, and as it is raised and carried onward by the apron it gradually settles down into the form of a loose and somewhat bulky sheet, and by said belt is carried entirely out of the water. While the disintegrated fibrous stock is held in suspension 75 in the water within the vat and directly over the apron 23, it is manipulated by hand to insure a uniform distribution of the stock in the water above the apron and thereby also 80 insuring the proper felting action. Otherwise stated, two men stand by the side of the machine, one on each side of the vat, and manipulate the fibrous stock which hangs in suspension in the water above the apron 85 until they get it uniformly distributed and the fibers in position to interlap and interlace together as they are permitted to collect on the apron as it approaches the top of the water and emerges therefrom, while this 90 felting action is further insured by the running of the water through the reticulate apron after it emerges from the water. Otherwise, and briefly stated, the mechanism of the machine itself is supplemented 95 by the said hand action to insure the proper felting action to get the best grade of fiber board. Approximately at the point where the collected sheet of fiber is carried out of the water, it is acted upon by the vibratory 100 tamping plate 55. This tamping plate, by its rapidly repeating pounding or tamping actions on the loose sheet-like body of fiber, packs the same down and very greatly decreases its thickness while at the same time 105 removing considerable water from the fiber. In this pressing action the tamping plate 55 finds a base of reaction against the slatted or open deck 32-33. The water pressed from the fiber and which runs from the fiber by 110 gravity, finds free downward escape through the meshes of the apron 23 and through the slatted underlying deck. In practice I have found that coöoperating rollers are not satisfactory for imparting initial compression to 115 the loose and bulky sheet of fiber, because the fibers in this loose condition have little cohesion and, hence, would tend to back up or accumulate in front of the rollers instead of passing between the same as fast as delivered thereto. This vibratory tamping plate, however, simply presses the underlying fiber together and does not otherwise displace the same or cause the fibers to be bunched up. The sheet of fiber or partially 120 completed flax felt after it has been partly compacted and has passed onward from the tamping device, is indicated by the character z^1 in Figs. 1 and 1^a. When this sheet z^1 is, by the traveling apron 23, carried between 125 130

the so-called primary pressure rollers 25 and 34, it is further compressed, and when it is subsequently moved between the so-called secondary pressure rollers 38 and 39 it is compressed to final compactness, and by wire coverings 54 is given a sort of tufted shape on both surfaces. These tufted surfaces are for many purposes desirable on the finished flax felt or board. For instance, when used 10 for insulation in ice chests or refrigerator cars where it is placed between the closely engaging walls, it affords a multiplicity of air cells or chambers on both sides of the felt. In passing between the said secondary 15 rollers 38 and 39, the edges of the felt or board are cut and trimmed by the cutting flanges 38^b of the roller 38 which overlap the ends of the overlying roller 39. The finished flax felt or fiber board is, as already indicated, 20 delivered onto the carrier 52 by means of which it may be delivered to a drier, if desired.

As is evident, the gathering boards 65 keep the loose fiber within the zone of action of 25 the tamping plate 55, the gathering boards 68 keep the fiber within the zone of action of the primary pressure rollers 25—34, and the gathering boards 71 keep the said fiber within the zone of action of the secondary 30 pressure rollers 38 and 39.

What I claim is:

1. In a fiber board machine, the combination with a vessel adapted to contain commingled liquid and fiber, of an apron driving means, an inclined endless traveling apron extending from a point below to a point above the upper surface of said liquid and operative to carry the collected fiber from the liquid in the form of a sheet, and 35 mechanical means independent of said apron driving means, operative to compact the fiber of said sheet approximately at the point where the same is carried out of said liquid, substantially as described.

45 2. In a fiber board machine, the combination with a vessel adapted to contain commingled liquid and fiber, of an inclined endless traveling apron extending from a point below to a point above the upper surface of said liquid and operative to carry the collected fiber from the liquid in the form of a sheet, a vibratory tamper operative to compact the sheet of fiber approximately at the point where it is carried from said liquid, and coöperating rollers operative on said sheet of fiber to further compress the same, substantially as described.

60 3. In a fiber board machine, the combination with a vessel adapted to contain commingled liquid and fiber, of an inclined endless traveling apron adapted to carry the wet fiber in the form of a sheet, and a vibratory tamping plate overlying said 65 apron and adapted to press and compact the

said sheet of fiber, substantially as described.

4. In a fiber board machine, the combination with a vessel adapted to contain commingled liquid and fiber, of an inclined 70 open deck and an inclined endless traveling reticulate apron working over said deck, both extending from a point below to a point above the upper surface of the liquid, and a vibratory tamper operative to press 75 and compact the sheet of collected fiber approximately at the point where it is carried from the liquid by said apron, substantially as described.

5. In a machine of the kind described, 80 the combination with a liquid containing vessel, of a coöperating toothed cylinder and toothed concave arranged for action on the fiber at a point below the upper surface of the liquid, substantially as described. 85

6. In a fiber board machine, the combination with a liquid containing vessel, of a coöperating toothed cylinder and toothed concave arranged for action on the fiber at a point below the upper surface of the 90 liquid, and an endless traveling apron extending from a point below to a point above the upper surface of the liquid and arranged to carry the fiber disintegrated by said cylinder and concave, from said liquid, 95 substantially as described.

7. In a fiber board machine, the combination with a liquid containing vessel, of a coöperating toothed cylinder and toothed concave arranged for action on the fiber at a 100 point below the upper surface of the liquid, toothed agitators operative on the fiber disintegrated by said cylinder and concave, and an endless traveling apron extending from a point below to a point above the upper surface of the liquid and arranged to carry the fiber delivered thereto by said agitators, from the liquid, in the form of a sheet, substantially as described.

8. In a fiber board machine, the combination with a liquid containing vessel, of coöperating toothed cylinder and toothed concave arranged for action on the fiber at a point below the upper surface of the liquid, a rotary toothed agitator operative 110 on the fiber delivered thereto from said cylinder and concave, a submerged perforate deck underlying said agitator, and an endless traveling apron extending from a point below to a point above the liquid and operating to carry the fiber delivered thereto by said agitator, from the liquid, substantially as described. 115

9. In a machine of the kind described, 120 the combination with a liquid containing vessel, of means for commingling the fiber in said liquid, an endless traveling apron extending from a point below to a point above the upper surface of the liquid and arranged to carry the fiber from the liquid 125 130

in the form of a sheet, gathering boards arranged at the opposite sides of said apron, and means for compacting the sheet of fiber carried from the liquid by said apron, 5 substantially as described.

10. In a machine of the kind described, the combination with a water containing tank, of an inclined open belt having its stock receiving portion submerged in said tank, relatively fixed carding teeth submerged in said tank in front of the receiving portion of said belt and from which the stock is delivered to said belt, and a toothed cylinder coöperating with the said carding teeth to card the stock below the surface of the water.

11. In a machine of the kind described, the combination with a water containing tank and an inclined open belt arranged to 20 carry the stock from a point below to a point above the surface of the water in said tank, a submerged support for the stock arranged to deliver the same onto said belt, carding teeth on said submerged support, and a toothed cylinder coöperating with said carding teeth to card the stock below the surface of the water.

12. In a machine of the kind described, the combination with a vessel adapted to 30 contain commingled liquid and fiber, of an inclined endless traveling apron having its

stock receiving portion submerged in the liquid of said tank and operative to carry the collected fiber from the liquid in the form of a sheet, and a vibratory tamper 35 working over the intermediate portion of said apron and operative to compact the fiber of the sheet carried by said apron.

13. In a machine of the kind described, a toothed cylinder to distribute the stock, 40 an open conveyer for receiving and distributing the stock, and means for keeping a portion of the conveyer submerged to wet the stock.

14. In a machine of the kind described, 45 the combination with a tank, an endless conveyer therein and guiding supports for supporting the discharge end of the conveyer above the water level in the tank, of means for distributing fiber on the conveyer 50 near the end of the latter, opposite the discharge end, and means intermediate the ends of the conveyer for compressing the fiber being carried by the conveyer toward the discharge end. 55

In testimony whereof I affix my signature in presence of two witnesses.

JAMES E. LAPPEN.
